MOLD.

Application filed December 19, 1925, Serial No. 76,416. Renewed May 22, 1928.

- The present invention relates to a permanent mold for casting metal articles, such as for instance sash weights, and has to do particularly with a molding apparatus which incorporates a plurality of individual molds into a single unitary apparatus and which is particularly adapted to the rapid and economical production of the cast metal articles in quantity.
- In the commercial casting of metal articles which must be produced cheaply and in large quantities the use of the sand mold, wherein it was necessary at each casting operation to form the mold with a suitable pattern and then withdraw the pattern before casting, is impracticable for quantity production due to the fact that it is expensive and is slow, and for these reasons the sand mold is being replaced by permanent molds made of metal such as iron or steel. In the use of permanent molds of this type no patterns are required, the molten metal being poured directly into the mold and suitable provision being made for discharge of the cast article and subsequent return of the mold to the proper condition for forming a casting. One of the advantages of permanent molds is the rapidity with which successive casting operations can be conducted in a single mold.
- For attaining quantity production, for instance in the casting of ingots, it has been proposed to nest a plurality of individual permanent molds about a common delivery trough so that a large quantity of the molten ingot metal from the ladle may be poured at one operation into the delivery trough from whence it will flow into the various molds in communication with the trough and will thus be formed into ingots. After the molten metal has cooled the nest of individual molds is disassembled and the ingots removed from the respective molds, after which the molds may again be nested about the delivery trough to receive a fresh charge of molten metal. This type of casting is of course adapted for accommodating a large quantity of molten metal at a single pouring operation and, due to the necessity of disassembling individual molds, is not adapted for casting operations which must be repeated at short intervals.
- Molding apparatus having a plurality of individual molds incorporated into a unitary apparatus and provided with means for opening the mold to facilitate discharge of the cast articles has been proposed for the casting of articles such as sash weights and the like. An important objection to apparatus of this type is the rather definitely limited number of articles which may be cast in such a mold at each operation. Molds of this character in present commercial use commonly consist of two interfitting parts, mold impressions formed in them and with a suitable runner and gates communicating with the individual mold impressions. In practice the mold impressions near the inlet end of the runner invariably fill completely while the remaining mold impressions are only partially filled or have not received any molten metal at all. This gives rise to the difficulty that it is impossible to convey the molten metal into the remote mold impressions before it chills to such an extent that these molds cannot be filled at all or at least are improperly filled, with the result that inferior castings are produced. This difficulty occurs even where the flow of molten metal from the runner into the individual molds is controlled by restricted openings such as orifices or the like. We have found that in commercial practice in the production of sash weights the number of weights which are being successfully produced at each operation is two.
- It is a principal object of this invention to provide a permanent mold of iron or similar material constituting a unitary apparatus which may at a single operation be brought into condition to receive molten metal or may at a single operation be opened to discharge the finished casting, and which is of such construction and is provided with passages and molds of such shape and arrangement that a plurality of articles, for instance as many as five or eight, may be successfully cast simultaneously and with great rapidity, the production of a single group of castings during continuous operation requiring less than a minute. To this end, the mold is built in two sections hinged together so that it is merely necessary to close or open the hinged parts in order to respectively put the mold into condition for receiving molten metal or to discharge finished castings from the mold. The pouring runner in the mold is vertical and the individual mold impressions communicating with the vertical filling trough are substantially horizontal, it being preferable, however, to have the mold impressions slanted slightly so that the remote end of each

mold impression is slightly lower than the end which is in communication with the runner. The mold impressions communicate with the filling runner through restricted passages or gates of cross section, smaller than the cross section of the runner. With this arrangement the flow of metal from the runner into each mold is relatively slow compared to the rate at which molten metal may be introduced into the runner. In operation, therefore, the runner becomes filled with molten metal substantially at the beginning of the pouring operation and is maintained full until all of the molds are filled. In this way complete filling of the remote molds is insured and also the molds are filled substantially simultaneously and at a substantially uniform rate of flow.

To provide for producing castings in the mold in rapid succession, the invention contemplates adequate cooling of the mold. Each section of the apparatus is provided with an adequate supply of cooling fluid, so that the heat derived from the molten metal is rapidly and effectively dissipated. It is an important object of the invention to provide a molding apparatus adapted for continuous operation which will be substantially free from cracking and like defects produced by reason of great temperature differences between the various parts of the mold. In order to effect this condition provision is made for conducting an adequate supply of cooling fluid into intimate heat exchanging relation with the molten metal in each of the individual mold impressions, the cooling fluid being separated from the molten metal only by a relatively thin wall of iron or similar heat transferring material. With this effective heat transferring arrangement the heat of the molten metal is rapidly and completely dissipated and the metal of the mold is kept at a more nearly uniform temperature throughout with the result that deterioration due to extreme temperature differences is avoided.

A further object of the invention is to provide a mold which permits the ready escape of the air in the mold as the metal is poured in, and which also permits a slight expansion of the mold as the metal solidifies so that the mold will not be subject to undue strains.

A further object of the invention is to provide a simple and effective device for ejecting the casting from the mold when the mold is opened after the metal has solidified.

We have illustrated a preferred embodiment of our invention in which Figure 1 is an elevational view showing a molding apparatus embodying our invention, the apparatus being opened so that the mold impressions may be seen; Figure 2 is a horizontal sectional view of the apparatus when closed to receive molten metal, the view being taken longitudinally of one of the mold im-

pressions; Figure 3 is a vertical sectional view of the apparatus taken on line 3—3 of Figure 2; Figure 4 is a sectional view taken on line 4—4 of Figure 2 showing the passages for directing the flow of cooling fluid; Figure 5 is a view similar to Figure 1 illustrating a modification; Figure 6 is an elevational view showing an open mold in modified form in which the water-cooling feature is omitted; Figure 7 is a sectional view taken horizontally through Fig. 10 showing the latch; Figure 8 is a section on line 8—8 of Figure 7; Figure 9 is an elevation of the closed mold looking from the left of Figure 7; Figure 10 is a side elevation of the closed mold; Figure 11 is a sectional view on line 11—11 of Figure 10, showing one form of ejector; Figure 12 is a similar view of a modified form of ejector; and Figure 13 is a detail view showing a portion of the casting produced in the mold.

Referring to the drawings, particularly to Figs. 1 to 4, the molding apparatus embodying my invention comprises two parts 1 and 2 hinged together at 3 so that the parts may be opened into the position shown in Fig. 1 or may be closed into the position shown in Fig. 2. The material of the respective sections of the apparatus is iron or other suitable metal of this nature. The mold impressions here shown are designed for the production of sash weights and are arranged one above the other as indicated at 4, and are slanted slightly out of horizontal position as shown. The respective sections of the apparatus each contain one half of the complete mold impression and upon closing of the sections into the position indicated in Fig. 2 the partial mold impressions in the respective sections cooperate to form complete molds for a plurality of sash weights, here shown as four in number.

Before closing the surfaces of the molds, the runner and gates are painted with a suitable composition to prevent the molten metal sticking to the molds. The two sections are held closed by any suitable clamp applied to the projecting tongues 4a.

Molten metal is then introduced into the filling runner 5 through the inlet opening or throat 6. Each of the mold impressions 4 communicates with the filling runner 5 through the medium of a constricted funnel-shaped delivery passage or gate 7 having its smaller end adjacent the mold impression 4. The capacity of the filling runner 5 is large relative to that of the funnel-shaped passages 7, with the result that upon introducing molten metal into the filling runner 5 the runner quickly fills and the metal flows from it through each of the funnel-shaped passages 7 into the respective mold impressions 4, the runner being maintained full by continued pouring. In this fashion all of the molds are filled simultaneously.

- While the filling runner is preferably vertical, it is under certain conditions possible to successfully operate the apparatus with the filling trough 5 horizontal, provided that the restricted passages 7 are properly designed. If these passages are of small cross-section and are tapered as shown into funnel-shape, it is possible to thus control the flow of molten metal from the filling runner into the respective mold impressions so that the remote molds are adequately supplied with metal. It will be understood, however, that in order to accomplish this, the shape and proportions of the funnel-shaped passages 7 must be carefully designed so that the metal as it is introduced into the filling runner 5 will not be unduly taken up by the first molds, with the result that a deficient supply is furnished to the remote molds.
- Each of the sections 1 and 2 of the mold is provided with a system of fluid conveying passages 8 for bringing water or other cooling fluid into intimate heat-transferring relation with the hot metal introduced into the mold impressions 4. The cooling water is admitted at the inlet 9 and by means of baffles 10 is directed in a tortuous path through the mold section from whence it issues at the discharge opening 11. The baffles 10 are so arranged that the cooling liquid flows longitudinally of the section a number of times equal to the number of castings being made, in this case four. The cooling liquid flows adjacent each mold impression throughout its entire length and is separated from it only by a relatively thin conducting wall 12 with the result that a rapid and effective transfer of heat from the mold during the casting operation is secured. An ample supply of cooling fluid is at all times provided and is continually being admitted through the respective sections of the apparatus. We have found that in an apparatus of this type it is possible to successfully cast as many as five sash weights at a single operation and that in continuous operation the apparatus may be employed to carry out ten complete casting operations every eight minutes.
- In Figure 5 I have illustrated a modified form of apparatus in which a greater number of castings, such as for instance eight to twelve, may be successfully formed. In this apparatus the filling runner 5 is centrally located and a group of mold impressions 4 is provided at each side of the filling runner. Thus by substantially doubling the length of the apparatus and otherwise utilizing the same construction as heretofore described, it is possible to double the number of castings which may be produced successfully at each operation.
- In Figures 6-12 inclusive, we have illustrated a modified form of mold wherein the water circulation is dispensed with. Molds of this kind cannot be used for the production of as many castings per hour as the water-cooled molds, but where a series of molds are used upon a carrier in such manner that each individual mold has an appreciable time for cooling before it again reaches the pouring station, solid molds may be advantageously used. The mold shown is a single mold for producing five castings at a single pouring.
- The mold is shown equipped with an improved form of latch which holds the mold sections closed through the action of a spring, whereby the air contained in the mold when the metal is poured will more readily escape, and which also permits of slight expansion of the mold as the metal solidifies. This latch member comprises a yoke 14 pivoted on one of the tongues 4^a, the cross bar of the yoke being provided with a hand screw 15, as shown in Fig. 7. Attached to the outer face of the other mold section, in position to overlie the other tongue 4^a is a stiff leaf spring 16. The free end of the spring is normally separated from the face of the tongue 4^a to the extent permitted by a bar or clip 17 attached to the face of the mold at the base of the tongue 4^a. When the latch is closed in the position shown in Fig. 7, the end of the screw 15 overlies the spring, and by turning the handle of the screw the spring may be compressed almost into contact with the tongue 4^a to hold the mold members close together but permit a slight separation. When the metal is poured in the mold the air in the mold will escape between the faces of the two mold sections which are not machined so as to make an absolutely airtight closure. As the metal expands on solidifying, the surface metal will be forced into the cracks on each side of the mold impression, thereby forming thin fins on the edges of the casting as indicated at 18 in Fig. 13.
- After the casting is removed from the mold the window weights or other articles cast in the mold impressions are broken off from the metal left in the runner and gates of the mold, the tapered form of the gate insuring that the break will be flush with the end of the window weight. After the window weights are separated they are tumbled in a barrel to remove the fins 18, the resulting window weights being solid throughout and with a smooth exterior surface.
- For facilitating the ejection of the casting from the mold we preferably provide an ejector pin of the form shown in Fig. 11 or the form shown in Fig. 12. The ejector shown in Fig. 11 comprises a pin 20 supported in a sleeve 21 which is threaded in the wall of the mold adjacent the runner 5, the inner end of the pin lying flush with the surface of the runner. The pin has a snug sliding fit in the wall of the mold and may be normally held in its outer position by a spring 22 enclosed in the sleeve 21. The pin projects beyond the end of the sleeve so that it may be readily

tapped with a hammer to eject the casting when the mold is open.

The ejector shown in Fig. 12 comprises a sleeve 23 threaded in the wall of the mold and an ejector pin 24 threaded in the sleeve with a thread of quick pitch and provided with a handle similar to the handle of the screw 15. To eject the casting it is only necessary to give a partial turn to the screw 24 to loosen the casting from the mold.

While we have shown our improved latch mechanism and ejectors in connection with the solid mold, it will of course be understood that they are equally applicable to the mold having the water circulation and are in fact used with such molds.

The operation of the apparatus and its principal advantages will be sufficiently understood from the foregoing description. One of the further advantages of the mold over the molds previously used in which the runner was horizontal and the molds vertical, is that the impact of the molten metal with the bottom of any cavity into which it runs tends to burn out the metal forming the surface of the cavity, making the article cast therein rough and irregular. If the mold impression of the article to be cast is vertically arranged, a slight burning of the metal will produce imperfect articles, whereas in our arrangement it is the runner which is vertical. The mold may be used until the bottom of the runner is actually burned through.

The present invention provides a molding apparatus intended particularly for the production of a plurality of castings at a single operation and for the production of such castings in continuous operation in rapid succession. The scope of the invention is defined in the appended claims.

We claim:

1. Molding apparatus of the class described comprising cooperating mold sections said sections being hinged together, a plurality of mold impressions formed in said mold sections, a vertically positioned filling passage formed in said mold sections for receiving molten metal and individual delivery passages communicating with said filling passage at different heights for delivering molten metal from said filling passage into said respective mold impressions.

2. Molding apparatus of the class described comprising cooperating mold sections, said sections being hinged together, permanent mold impressions in said sections and arranged one above the other, a vertically positioned filling passage in said mold sections for receiving molten metal and individual delivery passages communicating with said filling passage at heights corresponding to the positions of the respective mold impressions for delivering molten metal from said filling passage into said respective mold impressions.

3. Molding apparatus of the class de-

scribed comprising cooperating mold sections hinged together, permanent mold impressions therein, a filling passage in said mold sections for receiving molten metal, and individual delivery passages permanently in said mold sections for delivering molten metal from said filling passage into said respective mold impressions, said delivery passages being of cross section diminishing from the end of said passage communicating with said filling passage toward the end of said passage opening into the mold impression.

4. Molding apparatus of the class described comprising cooperating mold sections hinged together, a plurality of mold impressions in said mold sections, a vertically positioned filling passage in said mold sections for receiving molten metal, and individual delivery passages communicating with said filling passage at different heights for delivering molten metal from said filling passage into said respective mold impressions, said delivery passages being of cross section diminishing from the end of said passage communicating with said filling passage toward the end of said passages opening into the respective mold impressions.

5. Molding apparatus of the class described comprising cooperating mold sections hinged together, permanent mold impressions in said mold sections and slanted slightly out of horizontal position, a vertical filling passage in said mold sections for receiving molten metal, and individual delivery passages entering the higher ends of said mold sections and communicating with the said filling passage at different heights.

6. Molding apparatus of the class described comprising a pair of cooperating mold sections hinged together, a plurality of permanent elongated substantially horizontal mold impressions in said mold sections, a permanent filling passage in said mold sections for receiving molten metal, and permanent individual delivery passages in said mold sections for delivering the molten metal from said filling passage into said respective mold impressions, and a fluid containing chamber extending adjacent said mold impressions, baffles in said chamber extending alternately from the opposite walls thereof substantially between the mold impressions to form passages connected in series whereby cooling fluid is brought into heat exchanging relation with each of said mold sections, the temperature of the fluid being relatively uniform throughout the entire length of each section.

7. Molding apparatus of the class described comprising a pair of cooperating mold sections hinged together, permanent mold impressions formed therein, a permanent filling passage formed in said mold sections for receiving molten metal, individual delivery passages communicating with said filling

passage for delivering molten metal from said filling passage into said respective mold impressions, a fluid containing chamber adjacent the mold impressions, baffles arranged longitudinally between the mold impressions in said chamber and extending alternately from opposite walls thereof, these

baffles forming a tortuous passage for cooling fluids, and heat radiating fins arranged on the outer surfaces of the mold sections. ¹⁰

In testimony whereof we affix our signatures.
